UNITED STATES PATENT OFFICE

156,263

DESIGN FOR A CALCULATING MACHINE

Thomas O. Mehan, Park Ridge, Ill., assignor to
Victor Adding Machine Co., Chicago, Ill., a corporation of Illinois

Application January 19, 1948, Serial No. 143,869

Term of patent 14 years

(Cl. D64—11)

To all whom it may concern:

Be it known that I, Thomas O. Mehan, a citizen of the United States, residing at Park Ridge, in the county of Cook and State of Illinois, have invented a new, original, and ornamental Design for a Calculating Machine, of which the following is a specification, reference being had to the accompanying drawings, forming part thereof.

Fig. 1 is a side elevational view of a calculating machine, showing my new design;

Fig. 2 is a plan view thereof; and

Fig. 3 is a rear elevational view thereof.

I claim:

The ornamental design for a calculating machine, substantially as shown.

THOMAS O. MEHAN.
